T. S. SMITH, OF BOSTON, AND A. B. ELY, OF NEWTON, MASSACHUSETTS,
ASSIGNORS TO WILLIAM N. ELY, OF STRATFORD, CONNECTICUT.

Letters Patent No. 73,399, dated January 14, 1868.

IMPROVEMENT IN LET-OFF MECHANISM FOR LOOMS.

The Schedule referred to in these Letters Patent and making part of the same.

Be it known that we, T. S. SMITH, of Boston, and A. B. ELY, of Newton, in the State of Massachusetts, have invented certain new and useful Improvements in Let-Off Mechanism for Looms, of which the following, with the accompanying drawings, is a full and exact description—

Figure 1 being an end, and

Figure 2 a side elevation.

A A represent the frame; B, the yarn-beam; C, the cloth-beam. *b* is a gear-wheel on the end of the yarn-beam. *c* is a crank on the cloth-beam. The yarn is represented by red and blue lines. D is a gear-wheel, having a small pinion, *d*, meshing into the gear of the yarn-beam. E is an escapement-wheel, having a small pinion, *e*, meshing into the gear-wheel D. *e'* is a small crank-handle on the escapement-wheel, for winding up the slack yarn. F is the whip-roll, over which the yarn passes, and is made broad, and oscillates or rocks on bearings *f f*, on the frame. From the outer end of one of these bearings *f* depends an arm, I, which vibrates as the whip-roll rocks, the two forming a bent lever, with fulcrum at *f*. The relative angle of I to F may be altered and adjusted by the set-screw *f'*, according to the strain of the yarn and nature of the work. In the arm I is a slot, *i*, in which is placed the rear end of another arm, J, which is secured to I, at any part of the slot *i*, by a set-nut, *j*. The arm J projects forwards and downwards, meeting a lever, K *k*, pivoted to the frame at *l*, near its centre, and having at one end a dog, K, acting against the teeth of the escapement-wheel E, and at the other end a fork, *k*, between the tines of which rests the projecting forward end of the arm J. In many cases the lever K *k* may be dispensed with, and by a prolongation and alteration of the angle of the arm I, or by a prolongation of the arm J, J may be made to perform the operations of a dog to the escapement-wheel E. In the tines of the fork *k* are one or two set-screws, 2 and 3, to regulate the striking of the arm J, and ease any jumping motion of the dog K. Only one of these screws is needed, and both may be in some cases dispensed with. Instead of *k* being forked, J and *k* may be connected by a rod, regulated by a screw passing through the two, or by any suitable joint. *a* is a small arm, projecting forward from the arm I, at the bearing *f*, and taking into the forked shorter arm, *g*, of a lever, G *g*, pivoted to the frame, or to a bent arm, H, at *g'*, and having upon its forward and longer arm, G, a movable weight, L. The fulcrum of this lever is in a slot, *h*, and a set-nut enables it to be raised or lowered, and adjusted at pleasure. The weight L is adjustable on the arm G by means of a set-screw, *l*. The slot *h* may be dispensed with in many cases, and instead of the weight, a spring, G *s*, may be used, and made adjustable if desired; or the lever may be dispensed with, and a spring, extending from *g'* to *J*, may be used to hold up the arm J; or a spiral spring may be used, reaching from *s* to *g*, pressing upward against *a*; or any other lever and weight, or spring, adjustable, may be used, as convenience may dictate. The whip-roll may be constructed in any form, such that the yarn shall strain upon and over the rocking-arm of a lever.

The operation is as follows: The yarn, passing from the yarn-beam over the whip-roll, will pull more or less strongly upon and over the forward rocking edge. When the strain becomes sufficiently strong to overcome the weight L, or the springs, the lever-arm F will descend, and the arm I will move backward. As I moves back, the arm J will strike and press upon the lower tine of the fork *k*, and raise the dog K, and relieve the escapement-wheel E, which will revolve, and let off so much yarn as is wanted for the lay, when the weight L or spring will overcome the strain of the yarn, and the dog or pawl K will fall, and again engage with the escapement-wheel E, and the letting-off will cease till more is wanted, and the operation is repeated.

The escapement-wheel is made with the teeth or lugs at considerable distance from each other, and of form different from usual; and the lever or pawl having but one detent, the escapement is easily turned by the handle *e*, and the yarn on the beam wound up, whenever it may be too much loosed from any cause, without any change of position of the parts.

When the yarn-beam is full, the same strain and revolution will yield more yarn than when it is nearly empty, and the great difficulty consists in regulating the strain and the delivery of the yarn according to the fullness of the beam. In the beginning, the strain of the yarn should be retarded, or in the ending, quickened. For this purpose, either of the following devices may be used, according to the kind of loom or cloth. *n* is a stationary rod, running across the loom from side to side, between the yarn-beam and whip-roll, so that the yarn

shall pass under and partially round the rod at an angle, and this angle increases as the beam empties. The yarn passing round this rod will be held and retarded, as a hawser round a post, but this retardation or holding will grow less and less as the beam is emptied. This simple arrangement will answer in many cases. For other cases, *o* is a stationary rod, between the yarn-beam and whip-roll, upon which is hung a swinging rectangular brake, *P*, (with curved ends,) resting upon the yarn on the beam. Upon the upper and forward ends, running across, is a rod, *p*, which, when the beam is full, will be thrown forward to a position similar to or the same as the rod *n* in the former case. The yarn, passing up under rod *p*, will, as it strains, press the brake *P* upon the yarn of the beam, and retard its delivery, more or less, according to the fullness or otherwise of the beam, the strain decreasing and the friction diminishing as the yarn unwinds and the beam is emptied. These rods, *n* and *o*, are fixed to and supported by standards *N* and *O*, fastened to a shaft, *M*, passing through boxes *m*, and having a lever-handle, *m'*, held by a pin, *m''*. The object of this is to throw back the rods, so as to handle the yarn-beam more readily, but it may not be necessary.

Having described our invention, what we claim, and desire to secure by Letters Patent in let-off mechanism of looms, is—

1. The arm *J*, in combination with arm *I* and whip-roll *F*, when *J* is made adjustable in *I*, and the parts are severally arranged, substantially as described.
2. The whip-roll *F* and arm *I*, having an adjustable arm, *J*, in combination with the single detent-lever or pawl *K* and escapement-wheel *E*, when severally constructed and arranged for operation, substantially as described.
3. The lever *G* *g*, with or without adjustable fulcrum, and having an adjustable weight, *L*, as set forth, in combination with rocking-shaft roll *F*, all arranged substantially as described.
4. The combination of lever *G* *g*, weight *L*, arm *a*, levers *F* *I* *J* *K*, and escapement-wheel *E*, all arranged and operating substantially as and for the purposes set forth.
5. The rod *o* and brake *p* *P*, arranged in combination with and in relation to the yarn-beam and whip-roll, substantially as and for the purposes described.
6. The rod *o* and brake *p* *P*, in combination with a let-off mechanism operated by the strain of the yarn, substantially as described.
7. The mechanism for throwing back the rod *n* or rod *o*, to free the yarn-beam, substantially as described.
